UNITED STATES PATENT OFFICE

91,889

DESIGN FOR AN ANIMAL TOY

Matthew F. Lathers, Orlando, Fla.

Application February 13, 1934, Serial No. 50,705

Term of patent 7 years

To all whom it may concern:

Be it known that I, MATTHEW F. LATHERS, a citizen of the United States, residing at Orlando, in the county of Orange and State of Florida, have invented a new, original, and ornamental Design for Animal Toys, of which the following is a specification, reference being had to the accompanying drawing, forming part thereof.

I claim:

The ornamental design for an animal toy, as shown.

MATTHEW F. LATHERS.
